Inventor:

George T. Stewart
By Mount & Miller
Attorney.

UNITED STATES PATENT OFFICE.

GEORGE T. STEWART, OF DES MOINES, IOWA.

DESIGN FOR A VEHICLE SIGNAL CASING.

Application filed March 19, 1926. Serial No. 16,985. Term of patent 14 years.

To all whom it may concern:

Be it known that I, GEORGE T. STEWART, a citizen of the United States, residing at Des Moines, in the county of Polk and State of Iowa, have invented a new, original, and ornamental Design for Vehicle Signal Casings, of which the following is a specification, reference being had to the accompanying drawing, forming part thereof.

Figure 1 is a face view of a vehicle signal casing, showing my new design.

Fig. 2 is a top view thereof.

I claim:

The ornamental design for a vehicle signal casing, as shown.

GEO. T. STEWART.
